No 1,738.

George B. Owen's Design for Clock Case
Patented March 17, 1863.

Dec. 1738

George B. Owen, of New York, N.Y.
Letters Patent No. 1738 dated Nov. 17. 1803.

The schedule referred to in these Letters Patent and making part of the same.

To all whom it may concern:

Be it known that I, George B. Owen, of the city, county and state of New York, have invented or produced a new and original Design for a block base; and I do hereby declare that the following is a full, clear and exact description of the same reference being had to the accompanying drawings making a part of this specification, in which.

Figure 1, is a front or face view of my invention.

Figure 2, a side view of the same.

Figures 3, and 4, vertical section of the face or front part of the same, taken respectively in the lines x, x, y, y, Figure 1.

Similar letters of reference indicate corresponding parts in the several Figures.

The body A, of the clock case is of oblong quadrilateral form and rests upon a rectangular base B, the front and sides of which project beyond the body A, sufficiently far to admit of an inverted ovoli moulding a, being secured to it at the bottom of the body A. The upper part C, of the case is of semi-circular form and has a semi-circular moulding D, at its face side, said moulding being formed of two scotias h, h, two fillets c, c, and a true d, as shown clearly in Figure 3. This moulding D, is at the edge of the semi-circular part C, of the case and its ends rest on two square capitals c, c, of two semi-cylindrical columns ff, one at each side of the front of the case.

At the lower part of the face of the body A, of the case there is a projecting panel E, the top and sides of which are provided with a scotia moulding g, and at the centre of this panel there is an oblong projection h, a transverse section of which is a semi-ellipse.

On the front side of the base B, at its centre there is also a projecting panel E, of oblong form, its ends being comprised each of a semi-circle i, and two fillets j, j, and the centres of its upper and lower parts comprised each of a curved surface k, a portion of a circle, and two fillets l, l, the latter being connected by pro-

longed scotias m, m , to the fillets j , of the ends of the panel.

Having thus described my invention I claim as new
and desire to secure by Letters Patent:

The configuration of the parts herein shown and
described to form a new and original design for a clock case.

W^rthrees.
